ELECTRIC CIRCUIT BREAKER

Chauncey G. Suits, Schenectady, N. Y., assignor
to General Electric Company, a corporation of
New York

Application April 26, 1940, Serial No. 331,797

6 Claims. (Cl. 200—152)

My invention relates to electric circuit breakers and more particularly to circuit breakers where-in the circuit is interrupted in a high-pressure gaseous atmosphere and which circuit breakers may employ liquid contacts such as mercury.

Circuit breakers utilizing magnetic means for forcing an arc into an arc chute structure have been used heretofore. In such arrangements, it will be understood by those skilled in the art that the force exerted by the magnetic means is proportional to the square of the current. It is characteristic of a breaker of this kind to show a decreasing number of half cycles of arcing as the current to be interrupted is increased. The magnetic means for forcing the arc into the arc chute necessarily produces a large force at high currents, but a very small force at low currents and, hence, it is generally more difficult to obtain satisfactory interruption of the circuit at low currents. Under these conditions, wide separation of the contacts has been resorted to since, at low currents, the only force available for moving the arc into the arc chute is the convection force due to the buoyancy of the heated air in the arc column. I have discovered that arcs drawn in high pressure gases show a remarkable increase in convection effects which is fundamentally due to the fact that the buoyancy for a fixed temperature increases directly as the pressure, whereas the opposing factor, namely the viscosity, is substantially independent of pressure. It is clear, therefore, that low-current interruption will be greatly favored by the enhanced convection effect in high-pressure gases and that, at some high pressure, convection alone will serve as the sole means for forcing an arc into an arc chute or other arc-extinguishing structure. It would be desirable, therefore, to provide an electric circuit breaker which would interrupt the circuit as rapidly under low-current conditions as under high-current conditions and which would not require the large physical dimensions of circuit breakers of comparable rating used heretofore.

Mercury switches for low voltages and low current values have been used to some extent but have proved unsatisfactory in large-capacity circuit breakers. In most of the mercury switches of the prior art, the circuit was completed by flowing together two streams of mercury through a narrow bridge of some sort. It is well known that the current flowing through a conductor produces a magnetic field which exerts a force normal to the surface of such conductor. In the case of the two streams of mercury flowing together through a narrow bridge, this force at the instant of contact is made up of two components, one

which tends to separate the two streams of mercury and the other which tends to pinch off the small cross-section of mercury. Under low-current values, these forces are small and, hence, mercury switches of this type are satisfactory. However, at high currents, it becomes difficult to close the circuit through the narrow mercury stream because of this magnetic force and circuit breakers employing a mercury circuit have heretofore been impracticable for large interrupting capacities. It would be desirable to provide an electric circuit breaker employing a mercury circuit which would have a larger interrupting capacity than was heretofore possible since such a circuit breaker would eliminate the fire hazard associated with oil circuit breakers and would be much more compact than the so-called "air circuit breakers."

Accordingly, it is an object of my invention to provide a compact circuit breaker which will overcome the disadvantages noted above in connection with circuit breakers of the prior art.

It is another object of my invention to provide a new and improved circuit breaker employing liquid contacts which have an interrupting capacity considerably higher than was heretofore possible.

Still another object of my invention is to provide a circuit breaker which will interrupt the circuit in a very short interval of time, which interval of time will not vary substantially with variations in the current to be interrupted.

It is a further object of my invention to provide a circuit breaker including an arc chute wherein the circuit is interrupted in a gas under very high pressures so that the convection effect will force the arc into the arc chute to extinguish the same rapidly.

Further objects and advantages of my invention will become apparent as the following description proceeds and the features of novelty which characterize my invention will be pointed out with particularity in the claims annexed to and forming a part of this specification.

For a better understanding of my invention, reference may be had to the accompanying drawing in which Fig. 1 is a schematic diagram of a circuit breaker embodying my invention; Fig. 1a is a schematic illustration to aid in explaining the theory of my invention; Fig. 2 is a cross-sectional view of my circuit breaker at the instant the contacts are separated; Fig. 3 is a cross-sectional view of the circuit breaker in the closed-circuit position; Fig. 4 is a sectional view taken along line 4—4 of Fig. 3; Fig. 5 is a sectional view taken along line 5—5 of Fig. 3; and Fig. 6

is a perspective view of a portion of my circuit breaker.

Referring now to Fig. 1, I have illustrated my invention as applied to a circuit breaker 10 employing liquid contacts, such as mercury, which circuit breaker is adapted to interrupt the current flowing in electric circuit 11 and comprises a pressure-confining chamber 12. In order to interrupt the circuit, pressure-confining chamber 12 is tilted so as to cause separation of the liquid contacts therein. Any suitable means for tilting chamber 12 may be provided and, in Fig. 1, I have illustrated pressure-confining casing or chamber 12 as mounted in a cradle 13 which is pivotally mounted at 14 and arranged to be operated by any suitable mechanism, such as 15. The entire unit may be mounted on a suitable insulating base 16, if desired.

Referring now to Figs. 2 and 3, pressure-confining chamber 12 is illustrated as a metallic cylinder so constructed as to withstand relatively high pressures therein. One end of chamber 12 is closed by a metallic closure member 17 preferably welded thereto and associated with a suitable threaded electrode 18 through which connections to the external circuit may readily be made. A suitable passage 19 is provided in closure member 17 for purposes which will be hereinafter described and this passage is sealed off at 20 as by welding when the circuit breaker is completely constructed. The other end of pressure-confining casing 12 is provided with an electrode 21 extending therein and insulated therefrom by any suitable glass-to-metal seal 22 of rugged construction to withstand the high pressures within pressure-confining chamber 12. Preferably this seal 22 is of the type disclosed now Patent No. 2,299,750 issued Oct. 27, 1942, and broadly claimed in copending joint application Serial No. 305,666, filed November 22, 1939, on behalf of Albert W. Hull and Roy W. Moore, and assigned to the same assignee as the present invention.

As mentioned above, when two mercury surfaces flow together through a narrow bridge, point contact is made by virtue of the convex meniscus. In any conductor, the force due to the magnetic field of the current upon itself is normal to the surface of the conductor. As illustrated in Fig. 1a, this force may be resolved into two components, F_A which tends to force the mercury away from the junction box and F_B which tends to pinch off the small section of mercury. The resultant of the forces F_A and F_B is represented by F in Fig. 1a and is normal to the surface of the mercury stream. From the above discussion and particularly with reference to Fig. 1a, it will be observed that the forces are such as to prevent closure of the circuit under high currents. The forces which prevent the liquid contacts from closing the circuit will be rendered much less effective if as large a radius of curvature as possible is provided for the two contacting surfaces; that is, by having two relatively wide streams of mercury flow together so as to meet substantially on a straight line. With a narrow stream of mercury, this is impossible due to the effect of the meniscus. Therefore, I provide a cup-shaped member 23 of insulating material resiliently supported from closure member 17 by spring means 24. This cup 23 preferably of ceramic material is provided with a shallow end remote from the supporting means 24 which is closed by a barrier or dam 25 across the edge

of which the liquid contacts meet and separate on a straight line of substantial width during the circuit-closing and opening operations. Pressure-confining casing 12 is filled with mercury to the level indicated at 26 and it may be observed from Fig. 2 that barrier 25 has just interrupted the mercury circuit in so far as the mercury within and without ceramic cup 23 is concerned.

10 Electrode 21 is suitably connected to the mercury in ceramic cup 23 by a conductor 27, shown in detail in Fig. 6, which ends in a flattened portion 28 bearing against the wall of ceramic cup 23 adjacent spring 24 so that, by virtue of the force of spring 24, ceramic cup 23 will be held stationary and in proper position within pressure confining casing 12.

Since the resistance of mercury is relatively high compared with that of copper, for example, 20 considerable heating would occur under high currents if the current had to flow through a long mercury path for any length of time. However, I eliminate this difficulty by closing an auxiliary circuit in parallel with the liquid contacts after the initial closing of the liquid contacts at the barrier 25 of ceramic cup 23. Accordingly, conductor 27 is arranged to extend below electrode 21 and is constructed with a portion thereof in the form of a shoe 29 of relatively 30 large surface area. Further tilting toward the horizontal of pressure-confining chamber 12 in Fig. 2 will cause the electric circuit to be closed between shoe 29 and the walls of pressure-confining chamber 12, as shown in Fig. 3. By virtue 35 of the arrangement of shoe 29 relative to the walls of chamber 12, the cross-section of the mercury conductor at this point is very large while the length of conducting path is very short so that the internal resistance of the circuit 40 breaker becomes negligible during the closed-circuit condition. Furthermore, by this arrangement, the interrupting ability of the circuit breaker is enhanced since the resistance of the long mercury path is inserted in series with the circuit prior to interruption thereof.

45 In order to aid in extinguishing the arc drawn upon circuit interruption, a suitable arc chute 30 is provided comprising a plurality of relatively thin baffle plates 31 having the edges thereof extending close to and perpendicular with the barrier 25 of ceramic cup 23. This arc chute 30 is illustrated as being provided with ends 32 and 33 so as to prevent the arc gases from escaping adjacent the portion 28 of conductor 27 or adjacent the portion of conductor 27 associated 50 with electrode 21, thereby preventing the formation of any ionized path between these conducting members. Also, in order to prevent the arc gases from passing through arc chute 30 directly against conductor 27 and the walls of chamber 12, I provide a top cover member 34 for arc chute 30 which is arranged so that the arc gases may be vented through openings 35, shown in Fig. 5, at the upper corners of the arc chute. Furthermore, pressure-confining chamber 12 is provided with an insulating liner 36 so as to prevent any arcing to the walls of casing 12. This insulating liner 36 may be provided 55 only for the upper walls of chamber 12 if desired, as illustrated in Fig. 3 and supported by suitable means such as 37. Arc-chute 30 may be supported in any suitable manner from conductor 27 and, as will be understood by those skilled in the art, may be formed of any suitable insulating material. The interrupting

ability of my circuit breaker is further increased by providing suitable cooling or deionizing means 38 comprising alternate layers of flat and corrugated screen, for example, to aid the baffle plates 31 of arc chute 30 in cooling the arc gases. Preferably, the baffle plates 31 and the deionizing means 38 are finely subdivided so as to provide the maximum cooling of the arc and arc gases. However, these subdivisions must not be so small that they are destroyed as by melting.

In order to overcome the magnetic field due to the circuit configuration and thus permit the arc to be drawn across barrier 25 of ceramic cup 23 into the arc chute 30, I provide magnetic means in the form of a horseshoe-shaped electromagnet which comprises an iron horseshoe 39, mounted just outside the walls of ceramic cup 23 adjacent barrier 25, around which a plurality of turns 40 of conductor 27 are wound. Suitable insulating means 41 are provided between iron horseshoe 39 and the turns 40.

In order that my circuit breaker will interrupt an electric circuit in the same interval of time at low currents when the force due to the electromagnet comprising horseshoe 39 is very low as compared to high-current conditions when this force is very large, I fill pressure-confining casing 12 with a suitable gas, preferably hydrogen, under relatively high pressures of the order of several atmospheres and preferably ten or more. This gas may be supplied to chamber 12 through passage 19, which is thereafter sealed off at 20 as by welding. The high-pressure gas will greatly increase the convection effect so as to force the arc into the arc chute without depending upon the magnetic means for accomplishing this result. It will be understood by those skilled in the art that an arc chute used in connection with a circuit breaker operating in an atmosphere of hydrogen under high pressure may be applied to other circuit breakers and is not limited to circuit breakers having liquid contacts, such as mercury.

The operation of my new and improved circuit breaker will be considered first with reference to Fig. 3 where the electrical circuit is closed and the current flows from the bottom walls of chamber 12 through the short mercury path to the shoe 29 of conductor 27 which is associated with electrode 21, cylinder 12 being connected to the other electrode 18. The circuit through circuit breaker 10 may be interrupted by tilting chamber 12 in a counter-clockwise direction, whereupon the circuit through shoe 29 of conductor 27 is first interrupted and all the current must be carried by the long mercury path from the portion 28 of conductor 27 to electrode 18. Further tilting of casing 12 to the position shown in Fig. 2 causes a separation between the mercury within ceramic cup 23 and the rest of the mercury in chamber 12 by virtue of barrier 25 across which an arc is drawn. This arc is forced into arc chute 30 by the convection effect of the high-pressure gas in chamber 12 and, under high-current conditions, also by the force due to the magnetic means comprising horseshoe 39. The baffles 31 and the ionizing means 38 aid in rapidly quenching the arc, whereupon the circuit is interrupted.

In closing the circuit, the mercury within cup 23 and that in chamber 12 flow together over barrier 25 so as to approach each other in a

relatively wide path and meet on a straight line so that there is a greatly reduced tendency, as under the prior art arrangements, to prevent closure of the circuit by virtue of the action of the magnetic field on the fluid conductor at high currents.

While I have described a particular embodiment of my invention, it will be obvious to those skilled in the art that various changes and modifications may be made without departing from my invention and I, therefore, aim in the appended claims to cover all such changes and modifications as fall within the true spirit and scope of my invention.

15. What I claim as new and desire to secure by Letters Patent of the United States, is:

1. An electric circuit breaker for interrupting relatively high currents, a closed chamber, means including liquid contacts within said chamber arranged to draw an arc upon separation thereof to interrupt an associated electric circuit, a cup-shaped member of insulating material supported within said chamber having a relatively shallow portion at one end thereof, said shallow end being closed by a barrier of substantial width across which said liquid contacts are separated when interrupting said circuit, a conductor arranged to extend into said cup-shaped member to engage one of said liquid contacts, and spring means for biasing said cup-shaped member against said conductor.

2. In an electric circuit breaker, a chamber, means including liquid contacts within said chamber arranged to draw an arc upon separation thereof to interrupt an associated electric circuit, a rectangular ceramic cup supported within said chamber having one shallow end closed by a barrier of substantial width across which said liquid contacts are separated when interrupting said electric circuit, a conductor arranged to extend into said cup-shaped member to engage one of said liquid contacts, means for biasing said cup-shaped member against said conductor, and means for closing a circuit in parallel with the circuit through the liquid contacts subsequent to the completion of the latter to increase the current-carrying ability of said circuit breaker.

3. In an electric circuit breaker, a chamber, 50 means including liquid contacts within said chamber arranged to draw an arc upon separation thereof to interrupt an associated electric circuit, a rectangular cup-shaped member of insulating material supported within said chamber, one edge of which comprises a barrier of substantial width across which said liquid contacts are separated when interrupting said electric circuit, an arc chute comprising a plurality of baffles and deionizing means adjacent said barrier, magnetic means for forcing said arc into said arc chute so that high-speed interruption of said circuit may be obtained, and means for preventing said arc gases from coming into contact with conducting portions of said circuit breaker before they are sufficiently cooled and deionized by said arc chute.

4. An electric circuit breaker comprising a pressure-confining chamber containing hydrogen under a pressure of ten or more atmospheres, 70 means including liquid contacts within said chamber arranged to draw an arc upon separation thereof to interrupt an associated electric circuit, a rectangular cup-shaped member of insulating material supported within said chamber, one edge of which comprises a barrier of substan-

tial width across which said liquid contacts are separated when interrupting said electric circuit, an arc chute comprising a plurality of baffle plates adjacent said barrier, and magnetic means for forcing said arc into said arc chute under high-current conditions so that high-speed interruption of said circuit may be obtained, said arc being forced into said arc chute under low-current conditions solely by the convection effect of said hydrogen under pressure.

5. An electric circuit interrupter of the type capable of interrupting low currents as well as high currents comprising a pressure confining chamber, relatively movable contacts in said chamber arranged to draw an arc upon separation thereof, an arc chute comprising a plurality of baffle plates arranged in said chamber above said contacts, magnetic means for forcing said arc into said arc chute under high current conditions, and means for forcing said arc into said arc chute under low current conditions quickly to extinguish the same comprising hydrogen un-

der ten atmospheres or more of pressure contained in said chamber to produce a greatly enhanced convection effect forcing said arc into said arc chute.

6. An electric circuit interrupter of the type capable of interrupting low currents as well as high currents, comprising a pressure confining chamber, means including liquid contacts within said chamber arranged to draw an arc upon separation thereof, an arc chute comprising a plurality of baffle plates arranged in said chamber above said contacts, means for forcing said arc into said arc chute to extinguish the same under high current conditions, and means for forcing said arc into said arc chute under low current conditions quickly to extinguish the same comprising hydrogen under a pressure of ten atmospheres or more contained in said chamber so as greatly to enhance the convection effect forcing said arc into said arc chute.
